COMPUTING TABLE

COMMITTEE TABLE.

APPLICATION FILED DEC. 1, 1911

UNITED STATES PATENT OFFICE.

JOHN KNAUSE, OF LOCUST CORNER, OHIO, ASSIGNOR OF ONE-HALF TO CHARLES O. HAYS, OF LOCUST CORNER, OHIO.

COMPUTING-TABLE.

1,037,640.

Specification of Letters Patent. Patented Sept. 3, 1912.

Application filed December 1, 1911. Serial No. 663,407.

To all whom it may concern:

Be it known that I, JOHN KNAUSE, a citizen of the United States, residing at Locust Corner, in the county of Clermont and State of Ohio, have invented certain new and useful Improvements in Computing-Tables, of which the following is a specification.

The invention relates to a tabular calculating sheet for use in multiplying or dividing any given number within the limits of the table by the certain number, not exceeding two figures, for which the particular table is constructed; and the object of the invention is to provide a computing table by means of which such multiplication, or division can generally be accomplished by a mere inspection of the table.

In the accompanying drawings, forming part of this specification, Figure 1 shows the beginning of a table constructed in accordance with the present invention for multiplying by a mere inspection any number not exceeding four figures by the number 23 as a multiplier, or for dividing any number not greater than 229,977, by the number 23 as a divisor; Fig. 2 shows the first part or half of a computing table constructed according to the present invention for multiplying by inspection any number not exceeding four figures by the number 89 as a multiplier, or for dividing any number not greater than 889,911 by the number 89 as a divisor. Fig. 3, a continuation showing the second part or half of the table; and Fig. 4 shows the first part of a modified or extended form of a computing table constructed according to the present invention for multiplying by inspection any number not exceeding six figures by the number 99 as a multiplier, or for dividing any number not exceeding 98,999,901 by the number 99 as a divisor.

In the preferred or simpler form of the invention illustrated in Figs. 1, 2 and 3, the table is composed of a series of vertical columns and transverse rows of figures, the middle column of which is designated for distinction by the letter X placed at the head of the column, and contains in series down the column numbers corresponding to the two intermediate figures of any pro-

posed multiplicand, that is to say, the numerals indicating the ten and hundred figures thereof. In this column the same number 55 is occasionally duplicated, as shown; for the particular purposes of the table; and ciphers are prefixed when necessary to make a two-figure number.

To the left of the middle or X column 60 are provided ten several columns forming what is designated as Division A at the head of these columns, and the head of each column is further designated by the ten arabic digits or numerals, namely, 0, 1, 2, 65 3, 4, 5, 6, 7, 8 and 9, representing respectively the lefthand or thousand figure of any proposed multiplicand, so that this division might well be called the thousand division of the table. And to the right of the middle 70 or X column are also provided ten several columns forming what is designated as Division B at the head of these columns, and the head of each column is further designated by the ten arabic digits or numerals, 75 namely, 0, 1, 2, 3, 4, 5, 6, 7, 8 and 9, representing respectively the righthand or unit figure of any proposed multiplicand, so that this division might well be called the unit division of the table.

The several vertical columns are preferably separated for convenience of inspection by the vertical lines *a* and *b*, the vertical lines *a* dividing the several columns in Division A and Division B being preferably 85 distinguished from the vertical lines *b* at each side of the middle or X column and at each side of the table, which distinction may be made by using a single line for the former and a double line for the latter, as 90 shown, or by printing the respective lines in different widths or colors.

In the construction of the table, consecutive multiples of the multiplier to be used in a given table are entered in series from left 95 to right in the several rows of Division B. These multiples begin with 000 in the first row of the 0 column and thence in series to the right are entered the successive multiples as 023, 046, 069, etc., as shown in Fig. 1 100 for the multiplier 23; and so on in the several successive rows up to the largest multiple which can be expressed in three figures which is 989 located in row 04 in the X col-

umn, and column 3 in Division B. In this division, ciphers are prefixed to the smaller multiples when necessary to make a three-figure number. This multiple and row completes what may be termed and is designated Section 1 at either side of the table shown in part in Fig. 1, and the next succeeding multiple 1012 of the multiplier instead of being entered in the table in the same transverse row with the 989 multiple, is entered in the next row below; and the thousand figure 1 is omitted, so that this multiple appears in column 4 of Division B as 012, being the first multiple in the first row of Section 2 of the table, in which row the number 04 of the X column is repeated as the first number in Section 2. Beginning with the multiple (1)012 in Section 2 of Division B, consecutive multiples of the multiplier are entered in series from left to right and in successive rows as before, until the next thousand is reached, at which we have the multiple (1)978 entered in row 08 in the middle or X column and in column 6 of Division B, this number being the last number in Section 2; and the last three figures of the next succeeding multiple (2)001 are entered in column 7 of Division B in the next row below and become the first multiple in Section 3 of the table, for which row the number 08 is duplicated or repeated in the middle or X column of the table.

The several transverse rows are preferably separated for convenience of inspection by the transverse lines *c* and *d*, the transverse lines *c* dividing the several rows in each section being preferably distinguished from the transverse lines *d* between the several sections, which distinction may be made by using a lighter line for the former and a heavier line for the latter, as shown, or by printing the respective lines in different colors.

In the thousand Division A of the simpler form of table, only one row of multiples of the multiplier is entered and used in each section of the table. In Section 1, the multiple begins with 0 in the cipher column, and thence in series to the right are entered the successive multiples 23, 46, 69, and so on to 207 in column 9 of this division; and, for the purposes of the table, it is not necessary to prefix ciphers to the respective multiples to make a three-figure number as is done in Division B of the table. In the next section in Division A of the table, the row of numbers is each increased by one so that we have the series 1, 24, 47, and so on to 208 in Section 2; and the numbers 2, 25, 48, and so on to 209 in Section 3; and likewise for each succeeding section of the table.

In the use of the table, thus described, which is constructed for the multiplier 23, for multiplying any number not exceeding

four figures, as, for instance, 3147, the multiplicand is pointed off or separated mentally or otherwise into the thousand figure 3, the two intermediate figures 14 and the unit figure 7, as follows—3 14 7; and the three righthand figures of the product are readily found by mere inspection in column 7 of Division B and in the row designated 14 in the X column—the figures thus found in the table being 381; and the lefthand figures of the product are readily found by mere inspection in column 3 of Division A in the same Section 4 wherein the right-hand figures were found—which left-hand figures as shown by the table are 72: and by merely prefixing these left-hand figures to the right-hand figures, we have the proper product 72,381, from multiplying 3147 by 23.

From the foregoing description of the construction and use of the table, it appears that the two-figure numbers in the middle or X column are continued consecutively except when a section ends before the last row of multiples in Division B is completed, that is, before all the columns are filled; in which event the number in the X column must be continued or repeated until such line is completed, one row below in the first row of the next section, since the several multiples in the broken-line in Division B require the same number in the X column, but correspond to the numbers in Division A which are entered in the respective sections in Division B.

A complete table for multiplying by a mere inspection any number containing not more than four figures by the number 89 as a multiplier is shown in two parts in Figs. 2 and 3, Fig. 2 being part 1 and Fig. 3 being part 2 of the table, and part 2 being merely a continuation of part 1. In this table it will be seen that the several sections, (which are not designated excepting as they are separated by heavier transverse lines), are limited to two parallel transverse rows in Division B of the table; and it is evident generally that the size of sections varies inversely with the value of the multiplier, and that the number of sections in a given table is equal to the number of units in the multiplier.

In the use of the table illustrated in Figs. 2 and 3 for multiplying by mere inspection any number containing not more than four figures, as, for instance, 7859, the product can be readily obtained by merely separating the multiplicand as before described, as follows—7 85 9; after which the three right figures of the product are readily found in column 9 of Division B and row 85 as designated in the X column, the three figures thus found being 451; to which are prefixed the figures or number found in column 7 of Division A in the same section from which

the right-hand figures are taken, the prefix figures thus found being 699; thus making the complete product 699,451. In the use of the same table, if it be desired to multiply any number consisting of more than four figures by the number 89, the same can be done by beginning at the right and dividing the multiplicand into periods of four figures each, as, for instance, if the multiplicand is 2,785,349, it is first divided as follows: 278 5349, whereupon the multiplication of the first four figures, 5349, by 89 is made as before described by an inspection of the table and a partial product of 476,061 is found; 15 after which the multiplication of the next three figures, 278, (with a cipher prefixed to make four figures 0278), is likewise made by a mere inspection of the table and a second partial product is found to be 24,742, 20 which, being located four places to the left and added to the first partial product, gives the complete product of 247,896,061 for the multiplication.

These examples illustrate the general use 25 of computing tables constructed, as described above, according to the present invention; and general rules may be stated as follows for making any multiplication.

Multiplication.

30 *Case I.*—To multiply any number not exceeding four figures by any other number not exceeding two figures.

Rule.—Point off unit figure of multiplicand, find next two figures in the X column, then proceed to the right in same section to column headed by unit figure, and the number thus found will be the first three right-hand figures of product. Then proceed in 35 same section to the left to column headed by fourth figure of multiplicand, and the number thus found is prefixed to the right-hand figures already found and the product is thus completed.

45 *Case II.*—To multiply any number consisting of five or more figures by any other number not exceeding two figures.

Rule.—Beginning at the right, divide the multiplicand into periods of four places 50 each. Proceed with the four figures in the first period as directed in Case I for the first partial product. Then proceed with the figures in the next period in the same manner for the second partial product and write the 55 same four places to the left under the first partial product. Proceed with the figures in each additional period in the same manner, always writing each successive partial product four places to the left of its predecessor; 60 and the sum of the several partial products thus written is the complete product.

Case III.—When multiplier consists of three or more figures.

Rule.—Beginning at the right, divide the

multiplier into periods of two figures each. 65 Proceed with each period of the multiplier precisely as in Cases I and II, placing each successive partial product two places to the left of its predecessor, and the sum will be the complete product. 70

Note.—Should multiplicand contain fewer than four figures, prefix ciphers to make four places. After a little experience this will become merely a mental process.

From the foregoing examples and rules it 75 is evident that, by reversing the processes, the tables may be used for division as well as multiplication, the table constructed for a particular multiplier being employed for the same number as a divisor; and for such 80 use the normal capacity of the table is a dividend equal to 9,999 multiplied by the multiplier for which the particular table is constructed, as, for instance, 889,911 in the table constructed for 89 as the multiplier. 85 General rules may be stated as follows for such

Division.

Case I.—When the dividend is the capacity of the table or less. 90

Rule.—Point off three figures from right of dividend. Find remaining figures, or nearest less in first row of Division A, and proceed downward in the same column until 95 exact figures are found. The figure heading the column so found is first figure of the quotient. In Division B in the same section find the three figures pointed off, or the nearest number less. In the same row of 100 column X find the next two figures of the quotient, and, at the head of the same vertical column, find the fourth figure of the quotient. If the number referred to is less than the three figures of the dividend pointed off, subtract the one from the other and the difference will be the remainder. 105

Case II.—When dividend is greater than the capacity of the table. Begin at right of dividend and point off three figures, or as 110 many times three figures as may be necessary to reduce dividend to capacity of table. Then proceed with the left-hand period as in Case I. In the event a remainder is left, annex the next period to the remainder and 115 proceed as before for each successive period until operation is complete.

Case III.—To reduce a remainder to a decimal.

Rule.—Annex one cipher to remainder. 120 Proceed as in Case I to find a number one less than remainder with annexed cipher. The figure at the head of the column so found is first figure of decimal. In the same transverse section in Division B, find greatest number. The figures in the same row in the X column are the next two decimal places, and the figure at the head of the col-

umn containing said greatest number is the fourth decimal place.

Note.—Should dividend contain fewer than four figures, prefix ciphers to make 5 four places. Very rarely, the first period of the dividend is less than the smallest number in the same section; in which case, use the preceding section, and then subtract the largest number in Division B, in the same 10 section, from the first period with 1 prefixed.

A modified or extended form of table constructed according to the present invention is illustrated in Fig. 4. The principle of 15 construction in this extended form is substantially the same as for the simpler form, but admits the use of a multiplicand of six figures and the capacity of a section is ten thousand instead of one thousand. The columns in Division B contain consecutive 20 multiples of the multiplier up to the largest which can be expressed in four figures, and the numbers in Section 1 of the ten thousand Division A are the same as in Section 25 B except the prefixed ciphers are omitted in the multiples containing less than four figures and the multiples occurring in the last row of the section are also omitted. In Section 2 and in each succeeding section of 30 Division A, the numbers are respectively greater by a unit than the corresponding number in the preceding section; so that each section of Division A has always just ten rows of multiples. The intermediate 35 column includes a series of numbers each composed of three figures from 000 up to 999 in a complete table (not shown), the number in the X column in the row at the bottom of each section being repeated in 40 the row at the top of the section next below. And finally, an additional column is provided at the left of the table in which are entered the numerals 0, 1, 2, 3, 4, 5, 6, 7, 8 and 9, respectively, in the first ten rows 45 of each section, which additional column may be termed the hundred thousand column as the figures in each section correspond with the first figure of any particular multiplicand having six figures. For the 50 use of this extended table, the rule for multiplication is practically the same as explained above for the simpler table, and may be expressed as follows:

Rule.—Find first or unit figure of 55 multiplicand at the head of Division B and proceed downward in the same unit column containing this figure to the row containing the next three figures of the multiplicand in the X column, in which row and in the 60 same unit column will be found the first four figures of product. Find the fifth figure of the multiplicand at the head of the column in the ten thousand Division A and proceed downward to the same section from

which the partial product of the row has 65 been taken, and, in this section, find the row which contains the sixth figure of multiplicand in the hundred thousand column, in which row and ten thousand column will be 70 found the remainder of product to be prefixed to the partial product already found in the unit division.

I claim:

1. A computing table including a middle column containing a series of numbers severally representing the intermediate figures of a multiplicand, a lateral division containing a series of columns having therein a series of multiples of a particular multiplier severally representing the right-hand figures of a product of a multiplicand by the multiplier, and another lateral division containing a series of columns having therein a series of numbers severally representing the left-hand figures of said product. 75

2. A computing table including a middle column containing a series of numbers severally representing the intermediate figures of a multiplicand, a lateral division having ten columns headed by numerals in series 80 severally representing the unit figure of the multiplicand, and another lateral division having ten columns headed by numerals in series 85 severally representing a left-hand figure of the multiplicand; there being multiples of a particular multiplier entered in series and transverse rows in the columns of one division, ciphers being prefixed or the left-hand figure omitted when necessary to 90 make a given-figure number, and the first 95 multiple from which each several left-hand figure is omitted being entered in a row below the last preceding multiple to form 100 separate transverse sections, the last number in the middle column in each section being repeated as the first number in the next section when a row of multiples is broken; and there being a series of numbers in the 105 first section of the other division like the first row of multiples in the one division, 110 and a similar series of numbers each increased by one unit in each succeeding section of said other division.

3. A computing table composed of a middle column containing a series of numbers 115 severally representing the two intermediate figures of a four-figure multiplicand, a lateral division containing ten columns headed by numerals in series severally representing the unit figure of the multiplicand, and another lateral division having ten columns 120 headed by numerals in series severally representing the thousand figure of the multiplicand; there being a series of multiples 125 of a particular multiplier entered in series and transverse rows in the columns of one division, ciphers being prefixed or the left-hand figure omitted when necessary to make

a three-figure number, and the first multiple from which each several left-hand figure is omitted being entered in a row below the last preceding multiple to form separate transverse sections, the last number in the middle column in each section being repeated as the first number in the next section when a row of multiples is broken; and there being a series of numbers in the

first section of the other division like the 10 first row of multiples in the one division, and a similar series of numbers each increased by one unit in each succeeding section of said other division.

JOHN KNAUSE.
